UNITED STATES PATENT OFFICE.

LUTHER C. MEYERS, OF BRIDGETON, NEW JERSEY.

PRESS.

1,280,106.

Specification of Letters Patent. Patented Sept. 24, 1918.

Application filed June 7, 1918. Serial No. 238,672.

To all whom it may concern:

Be it known that I, LUTHER C. MEYERS, of Bridgeton, in the county of Cumberland, and in the State of New Jersey, have invented a certain new and useful Improvement in Presses; and do hereby declare that the following is a full, clear, and exact description thereof.

My invention relates to presses, such as cutting and punching presses of the open-throat type wherein the frame extends upward and forward from the base and overhangs the latter. As ordinarily made, press frames for this type of press have been made of a one-piece casting, and when as often happens, they are broken by accident, or overload, the entire frame is ruined and must be replaced, and at considerable loss because the whole frame is quite expensive. The object of my invention is to diminish the danger of breakage from overload and to avoid the loss of the entire frame should breakage occur, and my invention, broadly stated, consists in connecting the base and head members by tie rods which will take the tensile stresses which have to be borne by the frame of the type of presses in question and neutralize, or obviate the shearing stresses that tend to cause the frame parts sliding on one another.

In the accompanying drawings,

Figure 1 is a side elevation of a cutting press frame embodying my invention;

Fig. 2 is a front elevation thereof;

Fig. 3 is a detail view, in side elevation of a built-up form of tie rod; and

Fig. 4 is a side elevation of a press having a one-piece frame, embodying my invention.

Referring to the cutting press frame shown in Figs. 1 and 2, it will be seen that it is composed of a base member 10 having a plane, or flat top, a head member which is composed of two similar elements 11, which have half boxes 12 to furnish bearings for the shaft which extends from side to side of the press, and a body member 13, which, at its lower end rests upon the base at the rear thereof, the two being secured together, and at its upper end at each side has secured to it the two elements forming the head member 11, the abutting faces of the various members being plane, or flat. The body member 13 inclines upward and forward so that as will be seen from Fig. 1 of the drawings the ram reciprocating shaft overhangs the work on the bed of the press,

At each side of the press, and extending continuously from the bottom of the base 10 upward through an opening in the same and upward through openings in the body 13 and the head elements 11, and emerging on the top of the latter, is a tie rod situated so that it is intermediate the fulcrum, or bearing point upon which the body member, under load, tends to rock upon the base 10 and the line of thrust between the shaft supported by the head elements 11 and the base, so that the tie rods are practically in the line of greatest tensile strains and, hence, take the tensile stress which the frame must bear. In its lower portion, and for substantially half its length, the tie rod has a straight, vertical section 16, and at its lower, protruding end has a nut 17 that bears against the underside of the base 10, and its portion 75 is branched or forked, so that one arm 18 of the fork inclines upward and forward and the other arm 19 inclines upward and rearward, and both arms pass through the head element 11 and above the latter and both being thus oblique to the plane of the joint between the head element 11 and the body member 13. Each has a nut 20 that bears against the upper side of the head element.

Since the lower vertical portion 16 of the tie rod reaches through the base 10 and the body member 13 and extends at right angles to the plane of the joint between them, said portion 16 is under tensile stresses that are normal to said plane, and hence, no shearing stresses parallel to such plane are set up and accordingly, no tendency is caused for the sliding of the base and body members relative to each other. The forward inclination of the fork arm 18, by carrying it closer to the point of upward thrust exerted on the head element 11, enables it the better to resist such thrust by taking tensile stresses, but as it tends to "straighten up," or shift backward under the pull upon it, it sets up a tendency of the head element 11 to slide rearward over its bearing upon the top of the body member, but as the other fork arm 19 inclines in the opposite direction, and hence, under pull upon it, tends to move forward, it neutralizes the corresponding, but opposite action of the other fork arm 18, and, hence, horizontal shear, or tendency of head element to slide on the top of the body member is prevented.

The tie rods may have the integral, or one piece form shown in Fig. 1; or the built up

form shown in Fig. 3 where three separate rod sections are screwed into threaded holes in a block 21.

The ram slides in guides upon and at the front of the body member 13.

If from accident or overload any portion of the frame of the press breaks, the only part requiring to be replaced is the broken member, and, thus, there is no such serious loss as occurs when the whole frame is cast in one piece.

In Fig. 4 I show a press having a frame in which base 10^a, head 11^a and body 13^a are in one piece, which is apt, on overload, to break between the bed and the shaft bearings in the head, about the plane A—B. My forked tie rod 22 is applied, as shown in Fig. 4, in a manner and in relation to the stress lines, as in Figs. 1 and 2.

What I claim is:

1. A press frame for open throated presses comprising base, head and body members made of separate pieces, and a pair of tie rods, one at either side of the press, extending through and joining said pieces, said tie rods being situated in rear of the line of thrust between head and base members and forward of the fulcrum point upon which said connected members tend to rock and each tie rod being forked with one arm of the fork inclining forward and the other rear-

ward and both arms extending oblique to the plane of the joint between the frame members through which such arms pass.

2. A press frame for open throated presses comprising base, head and body members made of separate pieces, and a pair of tie rods, one at either side of the press, extending through and joining said pieces, said tie rods being situated in rear of the line of thrust between head and base members and forward of the fulcrum point upon which

said connected members tend to rock, and each tie rod being forked in its upper portion with one arm of the fork inclining forward and the other rearward and both arms extending oblique to the plane of the joint between the frame members through which such arms pass, and the lower part of the tie rod extending normal to the plane of the joint of the members through which such part passes.

3. A press frame for open throated presses comprising base, head and body members, the head member having bearings for the shaft, and a tie rod comprising a lower single member, and two upper diverging members, and reaching from the base to the head member, and secured thereto.

In testimony that I claim the foregoing I have hereunto set my hand.

LUTHER C. MEYERS.
